PAPER NAPKIN

Milford J. Taylor, Menasha, Wis., assignor to Wisconsin Tissue Mills, Menasha, Wis., a corporation of Wisconsin

Application March 11, 1950, Serial No. 8,488

Term of patent 14 years

(Cl. D59—2)

To all whom it may concern:

Be it known that I, Milford J. Taylor, a citizen of the United States, residing at Menasha, county of Winnebago, and State of Wisconsin, have invented a new, original, and ornamental Design for a Paper Napkin, of which the following is a specification, reference being had to the accompanying drawing, forming part thereof.

Fig. 1 is a view in perspective of a quarter-folded paper napkin, embodying my new design.

Fig. 2 is a view in perspective of the napkin of Fig. 1 as it appears when opened for use.

I claim:

The ornamental design for a paper napkin, as shown.

MILFORD J. TAYLOR.
